UNITED STATES PATENT OFFICE.

CHARLES S. COOK, OF MAPLEWOOD, MISSOURI.

STOVEPIPE ANCHOR.

Application filed October 11, 1919. Serial No. 329,977.

To all whom it may concern:

Be it known that I, CHARLES S. COOK, a citizen of the United States, residing at Maplewood, in the county of St. Louis and 5 State of Missouri, have invented a new and useful Stovepipe Anchor, of which the following is a specification.

My invention relates to new and useful improvements in stove pipe anchors, and an 10 important object of the invention is to provide a device which will securely retain a stove pipe within an opening in a wall or flue.

Another object of the invention is to provide a device which may be quickly installed, 15 which is strong, durable, inexpensive to manufacture and highly efficient in practice.

With the above and other objects in view 20 which will appear as the description proceeds, the invention resides in the combination and arrangement of parts and in the details of construction hereinafter described and claimed, it being understood that within 25 the scope of what is claimed, changes in the precise embodiment of the invention shown can be made without departing from the spirit of the invention.

In the accompanying drawings, forming 30 part of the description and wherein like numerals are employed to designate like parts throughout the several views.

Figure 1 is a side elevation of the invention installed; and

Figure 2 is an end elevation of the same. 35 In the drawings wherein for the purpose of illustration is shown the preferred embodiment of my invention, the numeral 3 designates in general my improved anchor, which is preferably formed from a single 40 strand of wire or other suitable material. The anchor is positioned within a stove pipe section 4 which includes the usual elbow 5 for changing the course of the pipe. The pipe section 4 is positioned within an opening 45 in a wall or flue 6 in such a manner that the inner end of the pipe section is flush with the inner face of the wall or flue.

My improved anchor 3 in the present instance is formed from a single strand of 50 resilient wire the substantial intermediate portion thereof being looped or coiled as at 7 to provide a pair of normally diverging spring arms 8 and 9. The natural tendency of these arms is to spring apart, but when 55 the anchor is positioned within a pipe section, these arms are slightly pressed toward

each other so that the relative upper arm 9 is arranged parallel to and in close proximity with the relative top of the pipe section, while the relative lower arm 8 is inclined 60 downwardly from the loop 7 towards the relative lower portion of the pipe section. It is to be noted that the coiled portion or loop 7 of the wire is arranged in close proximity or preferably flush with the outer face 65 of the wall 6 for a purpose which will presently appear.

The terminal of the arm 9 is bent upwardly to provide a flue engaging element 70 10 and this element snugly engages the inner face of the flue and the relative inner end of the pipe section 4. The lower arm 11 frictionally engages one wall of the pipe section 4, and is of a length to extend an appreciable distance within the flue 6 as at 75 11'.

In order to retain the pipe section 4, within the flue opening a retaining element 12 is engaged with the loop 7 of the anchor and extends to the outside of the stove pipe 80 and coils therearound as shown by Figure 1. However, in the present instance, the retaining element 12 assumes the form of a length of wire having its intermediate portion engaged with the loop 7, while its ends are 85 extended outwardly of the flue through an aperture 13 provided in the elbow 5. After the ends of the wire are threaded through the aperture, they are then carried downwardly upon opposite sides of the elbow to 90 be engaged with the crotch of the elbow, after which they are twisted or crossed and extended around opposite sides of the elbow. The terminals of the wire are then twisted so that the ends of the wire are snugly engaged with the flue to securely retain the 95 anchor in its proper position.

To install the device the arms of the anchor are urged towards each other to such an extent that the anchor may be readily 100 passed into the pipe section 4 until the flue engaging elements 10 and 11 are arranged within the flue, at which time pressure upon the arms 8 and 9 is relieved. The anchor is then moved outwardly of the pipe section 105 until the flue engaging elements 10 contact with the inner wall of the flue and the arm is arranged parallel and in close proximity with the relative top of the pipe section 4. A retaining element 12 such as 110 a length of wire is then engaged with the loop 7 of the anchor and the ends of the

wire are threaded through the aperture 13 in the elbow and secured to the pipe in the manner set forth. Manifestly, the anchor will at all times be urged outwardly of the 5 flue whereby its terminals or flue engaging elements 10 are securely engaged with the inner face or wall of the flue.

Having thus fully described the invention what is claimed is:

10. In combination with a stove pipe section an elbow connected therewith, a stove pipe anchor comprising a length of wire bent intermediate its length to provide a relatively straight arm adapted to lie parallel with 15 one wall of the pipe section, and in close proximity therewith, the relatively straight arm having a right angled end adapted to overlie one end of the stove pipe section and engage the wall of the chimney 20 flue, an angularly disposed arm forming a

part of the anchor, said angularly disposed arm extending to a point adjacent the opposite wall of the pipe section, a coiled portion connecting the angularly disposed arm and the relatively straight arm of the 25 anchor, and said angularly disposed arm terminating in a relatively straight portion adapted to frictionally engage the opposite wall of the stove pipe section, and a retaining element having connection with 30 the coiled portion of the anchor and passing around the elbow for anchoring the stove pipe in position.

In testimony that I claim the foregoing as my own, I have hereto affixed my signature 35 in the presence of two witnesses.

CHARLES S. COOK.
